GALVANOMETER

Donald N. Montgomery, Glendora, and Jack L. Thoss, Arcadia, Calif., assignors to Consolidated Electrodynamics Corporation, Pasadena, Calif., a corporation of California

Application January 17, 1957, Serial No. 634,666

10 1 Claim. (Cl. 324—154)

This invention relates to improvements in galvanometers of the type adapted to respond to alternating or oscillating voltages.

A typical galvanometer of this type comprises a light-weight fine wire coil held in suspension between a pair of stretched wires or ribbons respectively anchored at opposite ends to an enclosed galvanometer case. The suspension means defines the axis of rotary motion of the coil and supports a small mirror which is generally symmetrically arranged about this axis and for deflection responsive to rotation of the coil. A window in the galvanometer case aligned with the mirror enables incidence and reflection of a light beam by the mirror for sensing coil displacement.

The coil suspension means in the form of conductive wire or ribbon provides electrical leads to the coil, the upper suspension means conventionally being anchored to one terminal post sealed through an end of the galvanometer case and providing one external contact. The lower suspension means is generally attached to a lower terminal member located at the other end of the galvanometer case. The suspension assembly, including the terminals, suspension members and the coil suspended between the suspension members, is electrically insulated from the case.

It is a constant aim of those skilled in the art of making galvanometers to make the galvanometer as small as possible. The miniaturization of galvanometers provides many advantages in addition to the obvious advantage of light weight. Generally a plurality of galvanometers are set side-by-side in a recording instrument. Light rays incident upon the reflecting mirrors disposed within the galvanometers are deflected back to a photographic film and recorded as a plurality of separate traces, one trace for each galvanometer. A miniature galvanometer enables you to use a smaller camera and obtain more traces upon a given width of film. Also, miniature galvanometers can be placed closer together than larger galvanometers, giving better linearity in the recorded signals.

This invention contemplates a galvanometer having certain features and structure which enable the construction of a small galvanometer. Galvanometers constructed in accordance with these features may be less than one inch in length and approximately sixty thousandths of an inch in diameter.

The invention contemplates suspending a coil of many turns of wire within a galvanometer case. Instead of mounting the mirror to the suspension members, the mirror may be mounted upon the coil member. By mounting the coil in this manner the length of the suspension can be reduced, thus reducing the length of the galvanometer itself. The suspension assembly includes an upper terminal and a lower terminal of special construction. One of the terminals is constructed so as to be movable along the axis of the case. When adjustment of tension is required, the movable terminal is adjusted

2

longitudinally, and the tension on the suspension members varied.

The invention will be more clearly understood with reference to the accompanying drawings, in which:

5 Fig. 1 is a sectional elevational view showing the new galvanometer;

Fig. 2 is an elevational view showing the coil and mirror assembly;

Fig. 3 is an enlarged sectional view taken along lines

10 3—3 of Fig. 1; and

Fig. 4 is an enlarged sectional view taken along lines

4—4 of Fig. 1.

Referring to Fig. 1 which shows the galvanometer in section and in elevation, a casing 10 is provided for enclosing the suspension assembly. The casing is elongated in shape, having a length many times its width. The shape of the casing 10 may be cylindrical or any other shape to conform with the slots formed in magnet blocks, into which galvanometers of this type are usually placed.

15 An elongated coil member 12, consisting of many turns of wire, is suspended within the case 10 by an upper suspension means 14 and a lower suspension means 16. The upper and lower suspension means may be of round wire or of ribbon which is rectangular in cross-section, depending upon the resonant frequency of the system desired. A round wire suspension is generally used for a high frequency resonance, say above 1000 cycles per second. A ribbon suspension member can be used for lower resonant frequencies.

20 The upper suspension member 14, the coil 12, and the lower suspension member 16 each account for approximately one-third of the total suspension length.

25 Suspension members 14 and 16 are fastened to the coil 12 by stirrup connections 18 and 20, respectively, formed by passing the suspension wire through the opening of the coil and then soldering or otherwise connecting the wire back on itself. Insulating bobbins 22 and 24 of suitably stiff material are inserted into each end of the coil to provide support for the stirrup connections.

30 The open area of the coil 12, often called the window, is maintained at the proper dimension by the inclusion within the window of a reflecting mirror 26 shown more clearly in Fig. 2. The reflecting mirror can be directly bonded to the wires of coil member 12 or, in the alternative, a stiff insulating material can be bonded to the coil 12 and the mirror 26 mounted upon the insulating material.

35 A lens 28 is provided on the casing 10 adjacent mirror 26 so that incident light rays are directed to the mirror and reflected back through lens 28 to a recording medium (not shown).

40 Upper suspension member 14 is connected to a terminal 30. Lower suspension member 16 is connected to a terminal 32. Each of the terminals 30 and 32 is provided with extension members 34 and 36, respectively. The extension members 34 and 36 are offset from the axis of terminals 30 and 32. Extension member 34 is semi-circular in cross-section, with the flat edge extending along the axis of terminal 30 (see Fig. 3). Extension member 36 is also semi-circular in cross-section, with its flat side extending along the axis of terminal 32 (see Fig. 4).

45 The upper suspension member 14 and the lower suspension member 16 can thus be bonded by soldering or any other suitable means to the flat portions of extension members 34 and 36, respectively. This structure of the terminals permits the terminals, the suspension members 14 and 16, and the coil member 12 to be mounted within case 10 so that the axes of these members are along the axis of the case 10. Also, since the suspension members are mounted on the flat sides of the extension members, the length of the galvanometer is reduced

The suspension members are insulated from the casing 10 by means of an insulating member 38 and an insulating member 40 which electrically insulate the upper terminal 30 and the lower terminal 32 from the casing 10.

Provided in the lower portion of the galvanometer is a connector 42. A transverse hole is formed within the connector 42 into which is disposed a set screw 44. Set screw 44 is adapted to press tightly against terminal 32 when in the tightened position.

The entire case is filled with an oil which has a high index of refraction to use the advantage of greater deflections possible using the multiplying factor of the index of refraction, a well known principle. We prefer to use an oil having an index of reflection up to as high as four. An expansion tube 46 is disposed within a hole 15 formed in the side of casing 10 to provide for the expansion of the oil under changes in temperature.

A support member 48 is located at one end of the galvanometer adjacent the upper terminal 30 and insulator 38. When the galvanometer is placed on the magnet block (not shown) the flanges of the support member 48 rest upon the magnet block. Adjustment of the position of the galvanometer within the magnet block can be made by the provision of holes 50 within the support member 48.

The galvanometer structure is assembled by first connecting support member 48 rigidly to casing 10, and insulator 40 rigidly to casing 10 and connector member 42. Insulator 38 is then placed upon the upper extremity of casing 10 and upper terminal 30 cemented to the insulator 38.

Lower terminal 32, however, is movable. Therefore, lower terminal 32 can be moved axially within the casing 10 to adjust the tension exerted upon the suspension members. The tension adjustment is accomplished by loosening set screw 44, moving the terminal 32 in the proper direction to obtain the desired tension upon the suspension members, and then again tightening set screw 44.

We claim:

A miniature galvanometer assembly for operating in

any relative position comprising a tubular case, a mounting flange member secured at one end of the case for supporting the case and having arcuate slots for permitting angular adjustment of the mounting flange and case, first and second insulator members positioned in the respective ends of the tubular case, the insulator members having openings positioned along the longitudinal axis of the tubular case, a first terminal member extending through the opening in the first insulator member into the interior of the tubular case, a second terminal member extending through the opening in the second insulator member into the interior of the tubular case, means including a set screw for adjustably securing the first terminal in the insulation member, a flat elongated coil of wire, a pair of electrically conductive suspension members respectively linking the ends of the elongated coil and being secured to the terminal members, the first terminal member being positioned and secured by the set screw to hold the coil and suspension members in tension, a mirror mounted on the coil, an oil having a high index of refraction completely filling the case, and an expansion tube connected to and communicating with the interior of the case, whereby all air bubbles can be removed from the case with the tube permitting changes in the oil volume with changes in temperature.
